J. LOEFFLER.
VEGETABLE CUTTER.

APPLICATION FILED JUNE 28, 1920.

1,353,484.

Patented Sept. 21, 1920.

Inventor:—
John Loeffler.

John Loether
By John C. Higdon
Atty.

UNITED STATES PATENT OFFICE.

JOHN LOEFFLER, OF ST. LOUIS, MISSOURI.

VEGETABLE-CUTTER.

1,353,484.

Specification of Letters Patent. Patented Sept. 21, 1920.

Application filed June 28, 1920. Serial No. 392,404.

To all whom it may concern:

Be it known that I, JOHN LOEFFLER, a citizen of the United States, residing at St. Louis, in the State of Missouri, have invented certain new and useful Improvements in Vegetable-Cutters, of which the following is a specification containing a full, clear, and exact description, reference being had to the accompanying drawings, forming a part hereof.

My invention consists in the novel disclosure hereinafter particularly described and distinctly claimed.

The object of my invention is to provide an improved machine for slicing and cutting vegetables, which shall be simple and of low cost, and which shall be capable of efficiently cutting all kinds of vegetables into various shapes, for use in any of the well-known ways in which sliced vegetables are utilized.

In the drawings,

Figure 1 is a side-elevation of my improved vegetable cutter.

Fig. 2 is a top plan view of the same.

Fig. 3 is a side-elevation of one of the slitting-combs, detached.

Fig. 4 is a detail vertical section, taken on the line 4—4 of Fig. 2, and

Fig. 5 is an end-elevation of the device shown in Figs. 1 and 2.

The numeral 1 designates a horizontal knife-board, which may be made of wood or any suitable material, and of any desired size to adapt the device to cut vegetables of various kinds and sizes.

Opposite longitudinal guide-bars 2 are secured to the opposite edges of the said knife-board 1, by means of a tongue-and-groove connection 3 and glue, in the present illustration of my invention; the said guide-bars extending a considerable distance above the upper surface of said board to form a run-way and support for the slide-box 4, which is formed with a groove 5 in its outer walls, in which a tongue 6 at the upper edge of said guide-bars is located loosely, so that the said slide-box will be free to be moved longitudinally in cutting and slicing vegetables.

A tongue 7 at the lower edge of said slide-box 4 enters a groove 8 formed in the inner wall of said opposite guide-bars 2, so that said box will not only be properly supported by said bars, but will be free to move longitudinally thereon.

The said knife-board 1 extends from one end of the said guide-bars 2 to a point about midway of the length of the latter, where the inner end of said board is cut off at an angle, as indicated by the numeral 9, and a transverse steel cutter or knife 10 is set in a recess 11 formed in said board immediately above said angular or overhung end 9, flush with said board's top.

Common screws 12, or other fastenings, are used to fasten said knife 10 in place.

The cutting-edge of the said knife 10 projects free, so that it will be engaged by the vegetables to be cut or sliced, when the latter is reciprocated on said guide-bars above said knife, the said box being bottomless, to permit the vegetables to come into contact with said knife.

For controlling the thickness of the slices or strips of cut vegetables, I make the inner end of the slitting-comb carrier 14 adjustable with relation to the said cutting-knife 10, and positively lock said end in the desired adjustment against movement either up or down; and I positively move it either up or down, no matter if it be clogged with material.

The said slitting-comb carrier 14 also forms a movable part of the bottom or base of my machine, and I shall hereinafter call it the movable bottom member.

Said movable bottom member 14 is loosely or pivotally mounted at its outer end upon a cross-bar 15, which extends across the bottom and has its ends fixed beneath the under side of the said guide-bars 2 by means of common screws 16; and the same kind of screws are passed through countersunk holes 17 formed in said cross-bar and engaging said movable bottom member, to loosely (or pivotally) connect said end of said bottom member to the said cross-bar. Said countersunk holes 17 are sufficiently large to permit the said screws to move a limited distance therein, when said movable bottom member 14 is being adjusted. See Fig. 4.

The inner end of said movable bottom member 14 is supported, and forcibly moved up and down during the adjusting operation, by one or more thumb-screws 18 operating in threaded apertures formed in another cross-bar 19 that is fixed across the under-side of the said guide-bars 2 at a point near

to and beneath the inner movable end of the said movable bottom member, also by means of common screws, as 16.

The upper ends of said thumb-screw's 5 threaded shanks are reduced in diameter, or shouldered, and loosely passed through holes 20 in a rectangular plate 21 which is itself fixed to the free end of the said movable bottom member 14 by means of common screws or nails 22.

10 Countersunk heads 23 are formed upon the upper ends of the said reduced portions of the said thumb-screw shanks, flush with the upper surface of the said rectangular plate 21, so that when said screws are retracted the said heads will engage said plate and force it and the said movable bottom member 14 downwardly, in adjusting said member downwardly, to produce a thinner slice or strip of vegetable or fruit.

15 By the construction of the mountings for the said thumb-screws 18, just described, the reduced ends of same are loosely journaled in bearings in the said rectangular plates 21, but 25 the said countersunk heads 23 of said screws cause the said plates (and the said inner end of said movable bottom member 14) to travel with said screws, no matter in what direction the latter are turned.

20 Of course, moving said thumb-screws in one direction will force said movable bottom member's inner free end in one direction, and moving said screws in an opposite direction will force said free end in a corresponding direction; and thus the thickness of the slices or strips of cut vegetables 35 or fruit is easily controlled, as desired.

In the present showing of my invention, there are two of the said rectangular plates 40 21, each of which is in the form of a narrow strip of metal bent near the middle of its length to form a bracket that is L-shaped in longitudinal section or edge-elevation.

45 Hereinafter I shall term the said rectangular plates 21 comb-seat brackets, inasmuch as the shorter arms of same extend vertically in the space between the inner end of the said slitting-comb carrier 14 and the said transverse cutting-knife 10, and form 50 thereat a seat for detachable and interchangeable slitting-combs, 24.

One form of said combs is provided with

a series of vertical thin integral teeth which are set quite close together, as shown in Figs. 2 and 5, while a modified form of comb is 55 shown in Fig. 3, the latter having its teeth farther apart, so as to slit the slices produced by said transverse cutting-knife 10 in narrow or wider strips, as desired.

The said combs 24 have, in every case, the 60 same size of bodies, so that one comb may be substituted for another.

Or, if it is not desired to slit the slices, the comb may be removed from the comb-seat, and not used.

65 The lower edge of the body of the slitting-comb 24 rests upon the horizontal arms of the said comb-seat brackets 21, while the vertical opposite sides of said comb are held and guided by the adjacent vertical arms of 70 said brackets and the vertical end of the said slitting-comb carrier 14.

Opposite vertical grooves 25 are formed in the inner faces of the said longitudinal guide-bars 2, to permit the insertion and 75 removal of the combs 24. See Fig. 2.

The operation of my invention will be readily apparent from the above description.

80 I claim:

In a vegetable-cutter, a cutting-knife; a movable bottom-member, a fixed bottom member which carries said cutting-knife; a cross-bar fixed beneath said movable bottom member's inner end; rectangular comb-seat brackets fixed to the inner end of said movable bottom member, with their vertical arms arranged to form comb-seats thereat; a slitting-comb adapted to be supported in said comb-seats and thumb-screws threaded 85 through said cross-bar, and provided with heads and reduced journals at their upper ends, which permit said thumb-screws to rotate, and at the same time connect said comb-seat brackets to said cross-bar, to positively move said brackets and said cutting-knife up and down.

90 In testimony whereof I have signed my name to this specification in presence of two subscribing witnesses.

JOHN LOEFFLER.

Witnesses:

FRANCES E. MORRIS,
JOHN C. HIGDON.
